[57] **CLAIM**

The ornamental design for a hanging planter or similar article, substantially as shown.

DESCRIPTION

FIG. 1 is a top perspective view of a hanging planter showing our new design;

FIG. 2 is a side bottom perspective view taken from the right of FIG. 1;

FIG. 3 is a side bottom perspective view taken from the left of FIG. 1.

The partially shown cross-hatching pattern is understood to repeat uniformly across the surface of the container.

FIG. 3
